Application March 23, 1949, Serial No. 83,058

8 Claims. (Cl. 226—129)

1

This invention relates to apparatus for removing lids from containers and more particularly for the removal of lids from glass jars.

Occasionally it is necessary to reprocess food that has been prepared and packed in glass jars. One of the principal problems encountered in the reprocessing of the food is the removal of the lids from the containers. Ordinarily the lids are held in place by a rubber gasket which is urged forcefully against the walls of the jars, or a projection on their surface, by the lid which makes removal of the lids difficult. The large number of lids which must be removed, especially in the reprocessing of baby foods which are packaged in small jars, makes the removal of the caps from the jars a time consuming and expensive procedure in the reprocessing operation. The fragile nature of glass jars further aggravates the problem of removing the lids by automatic machinery because of the danger of breaking or cracking the jars and contaminating the food with particles of glass.

It is an object of this invention to provide a machine for the removal of lids from glass jars.

Another object of this invention is to provide a machine in which the jar is held firmly while the lid is lifted from its open end.

A further object of this invention is to provide a machine which will remove lids from glass jars rapidly and with a minimum of labor and supervision.

Still another object of this invention is to provide a machine for the removal of lids from glass jars in which the danger of breaking or cracking the jar is reduced to a minimum.

With these and other objects in view, this invention resides in a machine adapted to load the jars on a conveyor which carries them past a mechanism that punctures the lids of the jars. The jars are then rotated, while moving on the conveyor, against a plow which exerts a force gradually lifting the lid from the open end of the jar.

In the drawings:

Figure 1 is a plan view of the apparatus for removing lids from glass jars comprising this invention;

Figure 2 is a vertical, longitudinal sectional view along section line 2—2 in Figure 1;

Figure 3 is an end elevational view from the input end of the machine showing particularly the apparatus for puncturing the lids of the containers prior to their removal;

Figure 4 is a detailed perspective view illustrating the apparatus for puncturing the lids of the jars;

Figure 5 is a sectional view along the section line 5—5 in Figure 3 showing the star which stops the movement of the jars on the conveyor while the lids are being punctured;

2

Figure 6 is a detailed sectional view depicting a jar in position as the lid is being lifted from the jar; and,

Figure 7 is a diagram of the driving mechanism supplying the motive force for the conveyor and rotating mechanism.

Referring to Figure 2 of the drawings, the machine comprising this invention is illustrated having a frame 1 supporting a conveyor indicated generally by 2, adapted to carry the jars from the input end 3 of the machine to its discharge end 4. The conveyor 2 carries the jars past a puncturing element, indicated generally by 5, and a rotating mechanism indicated generally by 6, which urges the jars against a plow 7 as they move towards the discharge end 4 of the machine. A motor 8 is supported on the frame 1 and coupled to a speed reducer 9 to supply the power operating the machine in the manner hereinafter described.

Referring to the plan view of the machine in Figure 1, a feed table 10 is provided on which the jars to be opened for reprocessing of the contents are loaded at random. At the input end of the feed table 10 is a disc feeder 11 preferably tapering from its center towards its outer edges and which is driven by a central shaft 12. Preferably the outer edges of the disc feeder are slightly lower than the feed surface 10. The disc feeder 11 is positioned on the table 10 substantially tangential to the conveyor 2 for easy transfer of the jars from the disc feeder to the conveyor.

At the input end of the machine, a guide rail 13, elevated slightly above the surface of the feed table 10, follows the periphery of the disc feeder 11 substantially to its point of tangency with the conveyor 2. The guide rail 13 then passes across the conveyor and runs along its rear edge for the length of the machine to retain the jars on the conveyor. A second guide rail 14 is supported over the disc feeder substantially parallel with the guide rail 13 by brackets 15 from guide rail 13 and spaced therefrom at a distance slightly greater than the diameter of the jars. The rotation of the disc feeder 11 urges the jars outward and they are directed between the guide rails 13 and 14. Further rotation of the disc feeder moves the jars onto the conveyor 2.

To improve the operation of the disc feeder 11, a sleeve 16 is rotatably mounted on the shaft 12. A sweep arm 17 is attached to the sleeve 16 and extends therefrom towards the edge of the disc feeder. The sweep arm 17 is spaced above the upper surface of the disc feeder 11 for engagement with the walls of the jars placed on the disc feeder. Rotation of the sleeve 16 and sweep arm 17 is prevented by a lever 18 attached to the upper end of sleeve 16. Lever arm 18 is spaced sufficiently far above the surface of the disc feeder 11 to permit the jars which do not enter the space

between the guide rails 13 and 14 to pass underneath. A spring 19 secured to one of the brackets 15 and the end of lever 18 allows slight movement of the lever 18 and sweep arm 17 but does not permit rotation of the sleeve 16. Thus, the sweep arm 17 yieldingly engages the jars and directs them towards the periphery of the disc feeder.

The conveyor 2 is driven by a sheave 21 at the discharge end of the machine and passes over an idling sheave 22 keyed to a shaft 23 at the input end 3 of the machine. The sheaves 21 and 22 support the conveyor 2 at substantially the level of the outer edge of the disc feeder 11 to allow easy movement from the disc feeder. In addition, tracks 24 and 25 are supported from the frame 1, as shown in Figure 3, to provide a firm support for the conveyor 2 from the input end 3 to the discharge end 4 of the machine.

Conveyor 2 may be of any conventional type such as a belt conveyor, but in most instances it will be preferable to provide a conventional platform or tray conveyor consisting of a number of flat sections joined by suitable links. In this manner, a flat rigid surface providing a firm support for the jars is provided. A rear housing 27 is supported by frame 1 along the rear edge of the conveyor 2 for the mounting of the puncturing apparatus. A front housing 28 secured to the frame 1 along the front edge of conveyor 2 provides a support for the backing plate hereinafter described.

As the jars move along the conveyor it is desirable to stop them in an accurately determined position for the puncturing operation and to space the jars at the proper intervals on the conveyor 2 for the subsequent operations. For this purpose, a star wheel 29 is mounted on a vertical pin 31 which rotates in the rear housing 27. The star wheel 29 is provided with a plurality of arms 32 which pass through an opening in the wall of the housing 27 and extend over the conveyor 2. The relative position of the star 29 and the conveyor 2 is best illustrated in the sectional view shown in Figure 5. The arms 32 engage the jars moving on the conveyor 2 and hold them in the proper position for the puncturing operation. Rotation of the star 29 is prevented by a detent 33, operated by a cam in the manner hereinafter described. Detent 33 periodically moves towards the rear of the machine and disengages the arm 32 of the star 29 to allow it to rotate.

The actual puncturing of the lids of the jars is accomplished by means of a plunger 34 on the end of a rocker arm 35 over the conveyor 2, as shown in Figure 4. The rocker arm 35 is pivotally supported by a bracket 36, secured to the upper surface of the rear housing 27 and extending upwardly therefrom. At the rear end of the rocker arm 35, a post 37 has a roller 38 rotatably mounted at its lower end. Roller 38 is adapted to travel on a wedge 39 on the upper surface of a cam operated lever 41. Lever 41 pivots in a horizontal plane about a pin 42 extending upwardly from the upper surface of the housing 27.

Lever 41 extends from the wedge 39 past the pin 42 towards a cam 43. A cam follower 44, rotatably mounted on the end of the lever 41, engages the periphery of the cam and actuates the lever. At the end of lever 41, opposite the cam follower 44, is a roller 45 mounted on the end of the lever in a vertical position. Roller 45 rolls along the upper surface of the housing to support the lever against the force exerted by the roller 38 during the puncturing of the lids. The

detent 33, which prevents rotation of the star 29, is mounted on the lower surface of the lever 41 as illustrated in Figure 3.

Lever 41 is continually urged towards the rear of the housing 27 by a compression spring 46, compressed between ears 47 and 48 extending from the surface of the housing 27 and lever 41 respectively. The force of compression spring 46 maintains the cam follower 44 forcefully against the cam 43 and allows accurate control of the movement of the lever 41 by the cam.

Referring to Figure 1 of the drawings, the cam 43 is shown in a position just before the cam follower 44 of the lever arm engages the wedge 49 on the outer edge of the cam. The wedge 49 forces the cam follower 44 outward and operates the lever 41 to depress the plunger 34. Immediately following the wedge 49 is a depression 51 which allows the cam follower to move towards the front of the machine and thereby disengage the detent 33 from the star 29. The cam 43 is driven by a cam shaft 52 which in turn is driven by the motor 8 in the manner hereinafter described.

The mechanism for rotating the jars as the lids are lifted from them is best illustrated in Figures 1 and 2. A plurality of moving endless belts 53 are mounted on sheaves 54 and 55 which rotate integrally with a gear shaft 56 and the cam shaft 52 respectively. The shafts 56 and 52 turn in bearings 57 mounted on the frame 1. In the particular form of the invention shown, the shafts 56 and 52 support the sheaves 54 and 55 in position for the belts to move in the direction of travel of the conveyor above the rear edge of the conveyor and engage the walls of the jars nearest the rear edge of the machine and urge them in the direction of movement of the conveyor and thereby tend to rotate them as they move through the machine. A take-up roller 58 may be provided for adjustment of the tension on the endless belts 53.

A backing plate 59, best illustrated in Figure 6, is positioned above the forward edge of the conveyor 2 directly opposite the belts 53. The rear surface of the backing plate 59 is preferably covered with a sheet 60 of soft material, such as rubber, for engagement with the walls of the jars. The backing plate is slidably mounted to allow movement towards the rear of the machine on plungers 61 which slide in sleeves 62, rigidly supported by the front housing 28. The front end of each of the sleeves 62 is closed by a bushing 63 which serves as a base for springs 64 without in the sleeves urging the plunger towards the rear of the machine. The rearward movement of the plungers 61 is limited by stop nuts 65 on the forward end of the plunger which engage the bushing 63. The position of the stop nuts 65 on the plunger may be varied as necessary for the proper operation of the backing plate 59 for the particular size of the jar being opened.

Directly above the rotating belts 53 is a plow 7 positioned for engagement with the lid of the jars. The plow 7 is tapered and increases in thickness towards the discharge end of the machine. In most instances, it will be desirable to position the plow 7 for insertion between the shoulder on the glass jar and the lid. As the jar moves towards the discharge end of the machine the increasing thickness of the plow will pry the lid from the jar. Supported on the backing plate 59, directly opposite the plow 7, is a hold-down bar 66 which extends over the tops of the lids of the jars as they pass on the conveyor

2. In those instances in which there is no shoulder for the plow 7 to bear against to prevent lifting of the jar, the hold-down bar 66 will serve this function and enable the lid to be lifted from the jar.

The arrangement for transmitting power from the speed reducer 9 to the rotating mechanism and the conveyor is illustrated diagrammatically in Figure 7. A pulley 67 is driven by the shaft of the speed reducer 9 and in turn drives a pulley 68 by means of a belt 69. Pulley 68 is mounted on a gear shaft 71 on which a horizontal beveled gear 72 is mounted for engagement with a vertically beveled gear 73. The gear 73 is keyed to the shaft 56 and drives the sheaves 54 over which the rotating endless belt 53 passes. Endless belt 53 in turn drives the sheave 55 mounted on the cam shaft 52. The turning of cam shaft 52 produces a similar rotation of the cam 43 and operates the positioning and puncturing mechanism.

A pulley 74 mounted on the gear shaft 71 operates a speed reduction mechanism, consisting of a large sheave 75 and a small sheave 76 on a shaft 77, through a belt 78. A belt 79 is driven by sheave 76 and turns a pulley 81, keyed to a shaft 82 on which the sheave 21 is mounted. Sheave 21 drives the conveyor to move the jars from the input to the discharge end of the machine.

The rotation of the sheave 22 at the input end of the machine resulting from the movement of conveyor 2 turns the shaft 23 in bearings 83 mounted on the input end 3 of the machine. Referring to Figure 3, the shaft 23 turns a pulley 84, keyed thereto, over which a belt passes and drives a sheave 85 which is keyed to the shaft 12 of the disc feeder 11. Thus, the rotation of the conveyor will cause the disc feeder 11 to rotate at a slower rate depending upon the diameters of the pulleys over which the drive belts pass.

In the operation of the machine, the motor 8 is started which causes the conveyor 2 to move from the input to the discharge end of the machine and rotate the disc feeder 11. The rotation of the gear shaft 71 operates through the beveled gears to turn the shaft 56 and rotate the sheaves over which the endless belts 53 pass. The endless belts 53 rotate the cam 43 as described above.

The jars to be opened are placed on the table 10 at random and pushed onto the disc feeder 11. Rotation of the disc feeder results in a continuous movement of the jars into the space between the guide rails 13 and 14. Any jars which do not enter the space between the guide rails pass under the lever 18 and are urged towards the outer edge of the disc by the sweep arm 17. The jars passing between the guide rails 13 and 14 move on the disc until they engage the conveyor 2 and continue towards the discharge end of the machine on the conveyor 2.

Movement of the jars on the conveyor is interrupted by the star 29 which extends outwardly over the conveyor. The star holds a single jar directly below the puncturing arm 34. As the cam 43 rotates, the wedge 39 on its periphery engages the cam follower 44 to move the end of the lever 41 nearest the input end of the machine. The wedge 39, on the surface of the lever 41, engages the roller 38 and lifts the post 37 as the wedge 39 moves toward the front of the machine. Rocker arm 35 is thereby rotated to lower the plunger 34 through the lid of the jars.

Continued rotation of the cam 43 results in

the cam follower 44 moving into the depression 51 on the surface of the cam. The end of the lever 41 is then urged towards the rear of the machine by the compressed spring 46 and the detent 33 on the lower surface of the lever 41 disengages the star 29 and permits it to rotate one-quarter turn. As the cam 43 continues to rotate, the cam follower 44 engages the circular portion of the cam which moves the detent 33 into the normal position illustrated in Figure 5.

As the jar with the punctured lid moves on the conveyor towards the discharge end of the machine, it is engaged by the endless belts 53. The driving mechanism is adapted to move the belts 53 more rapidly than the conveyor 2 to urge the rear walls of the jars in the direction of travel of the conveyor and tend to rotate the jars in a clockwise direction as viewed in Figure 1. The forceful contact of the forward wall of the jar against the stationary back plate 59, which is preferably covered with a soft material having a high co-efficient of friction such as rubber, results in a strong force rotating the jars and moving them against the plow 7.

As the jars rotate, the forward edge of the plow 7 enters the space between the shoulder of the jar and the edge of its lid. The gradually increasing thickness of the plow 7 towards the discharge end of the machine and the movement 30 of the jar on the conveyor results in the exertion of constantly increasing lifting force on the lid of the jar. Moreover, rotation of the jars causes the force to be exerted at successive points around the periphery of the lid of the jar. Upward movement of the jar resulting from the force exerted by the plow 7 is prevented by the hold-down bar 66. The jars move from the discharge end of the plow with the lids resting lightly on their top. In some instances it may be desirable to shape the plow to lift the lid completely from the jar and discard it to one side of the conveyor.

While this invention has been described in detail with respect to a particular modification of the invention, it is to be understood that the concept of this invention is not limited to those details, but is determined by the scope of the appended claims.

We claim:

1. An apparatus for removing lids from sealed jars comprising conveying means adapted to carry the jars through the apparatus, cam actuated means for puncturing the lids preparatory to unseating the lids and positioned above the conveyor at a first station, a stationary inclined plow positioned at a second station to engage lid periphery between outer junction of lid and jar, endless belt means opposite the plow for rotating the jar toward the plow, and power means driving the conveyor means to move the jar past the plow, actuating the puncturing means, and driving the jar rotating belt means.

2. An apparatus for removing lids from sealed jars having a shoulder comprising conveying means adapted to carry the jars through the apparatus, cam actuated means for puncturing the lids preparatory to breaking seal between the lids and the jars positioned above the conveyor at a first station along the conveyor, a flat surfaced, inclined stationary plow positioned for insertion between the jar shoulder and the sealing lid periphery, at a second station along the conveyor, an endless belt opposite the said second station for engaging one side of the jar and moving to rotate the jar toward the plow, a stationary

plate beneath the said second station for bearing against the side of the jar opposite the endless belt to cooperate with the belt in rotating the jar, and power means concurrently driving the conveyor means to move the jars, actuating the puncturing means and rotating the endless belt.

3. Apparatus for removing lids from sealed jars having a shoulder comprising a conveyor adapted to carry the jars through the apparatus, cam actuated means at a first station along the conveyor for puncturing the lid to break seals between lids and jars, a flat surfaced, inclined plow at a second station along the conveyor positioned for insertion between the lid periphery and the shoulder of the jar, guide means for engaging the jar opposite the plow to hold it in place on the conveyor, an endless belt opposite said second station movable in the same direction as the conveyor and at a higher rate for engaging the wall of the jar, a plate adjacent the second station engaging the wall of the jar opposite the endless belt cooperating with the belt to rotate the jar towards the plow as the jar moves on the conveyor, and power means driving the conveyor, and endless belt and actuating the puncturing means.

4. Apparatus for removing lids from sealed jars having a shoulder comprising a conveyor on which the jars travel, a cam actuated arm at a first station periodically interrupting the movement of the jars positioned at said first station and in a fixed position, a cam actuated pin at the first station adapted to puncture the lid of the jar while the jar is at the fixed position, a flat surfaced, inclined plow at a second station along the conveyor positioned for insertion between the lid and the jar shoulder and adapted to raise the lid periphery as the jar progresses on the conveyor, an endless belt opposite the said second station for engaging the jars and moving in a direction to rotate them against the plow, a plate positioned opposite the belt and adjacent the plow to press the jar against the belt, the surface of said plate having a high coefficient of friction to resist relative motion between the wall of the jar and the plate, resilient guide means urging the plate toward the jar, and a source of power driving the conveyor and endless belt and operating the cam to actuate the positioning arm and puncturing pin.

5. In apparatus for the removal of lids from sealed jars, a conveyor for carrying the jars through the apparatus, an intermittently rotating star positioned at a first station having arms extending across the conveyor to stop the movement of the jars at a fixed position, a puncturing pin positioned above the conveyor at the fixed position, said star and said puncturing pin being operated by a cam whereby the star rotates after the pin has punctured the lid to allow the jar with the punctured lid to move on the conveyor and to stop the next jar at the fixed position, rigid inclined plow means at a second station for insertion between jar and lid, an endless belt engaging the wall of the jar and moving towards the plow to rotate the jars against the plow, a backing plate engaging the jar opposite the belt, and resilient means urging the plate towards the jar to press it against the moving belt.

6. A method of removing lids from sealed glass jars having a shoulder comprising first punctur-

ing the lid to break the seal, inserting a plow between the shoulder and the lid periphery, rotating the jar against the plow, and simultaneously exerting an increasing force over a substantial portion of a revolution of the jar against the lid with the plow to lift the lid from the jar.

7. In an apparatus for the removal of lids from sealed jars of the type having a belt conveyor for carrying jars through the apparatus and wherein the belt is positioned tangential to a rotary disc, a disc for depositing jars on the belt conveyor, rotatable shaft means keyed to the disc, a yieldingly rotatable sweep arm mounted on the shaft above the disc, spaced guide rails along the conveyor and extending over the disc, and power means for rotating the shaft to move disc, arm and conveyor belt whereby the jars may be directed between the rails and onto the conveyor.

8. In apparatus for removing lids from sealed jars, the combination comprising disc means mounted upon a rotary shaft for receiving jars and depositing the same upon a conveyor, sweep means engaging the shaft above the disc to yieldingly urge jars to the periphery of the disc, a conveyor for carrying jars through the apparatus, the conveyor being substantially tangential to the periphery of the disc, spaced guard rails along the conveyor extending over the disc whereby upon rotation of the disc jars may be directed between the rails and onto the conveyor, a cam actuated arm periodically interrupting the movement of the jars positioned at a first station along the conveyor in a fixed position, a cam actuated pin at the first station adapted to puncture the lid of the jar and break the seal while the jar is at the fixed position, a fixed plow of flat inclination positioned at a second station for insertion between the lid and the jar and adapted to raise the lid as the jar progresses on the conveyor, an endless belt opposite the second station along the conveyor engaging the jars and moving in a direction to rotate them against the plow, a plate positioned opposite the belt and adjacent the plow to press the jar against the belt, the surface of said plate having a high coefficient of friction to resist relative motion between the wall of the jar and the plate, and a source of power concurrently driving the disc, conveyor and operating the cam to actuate the positioning arm and puncturing pin.
